UNITED STATES PATENT OFFICE.

HARRY G. JOHNSTON, OF PLAINS, MONTANA.

RAILWAY SWITCH.

Application filed October 26, 1921. Serial No. 510,541.

To all whom it may concern:

Be it known that I, HARRY G. JOHNSTON, a citizen of the United States, residing at Plains, in the county of Sanders and State 5 of Montana, have invented certain new and useful Improvements in a Railway Switch, of which the following is a specification.

This invention relates to railway switches and more particularly to electrically operated switches to be controlled by the operator of the railway car whereby the throwing of a switch may be accomplished in a manner that will insure positive movement of the switch element.

15 Other objects of the invention will appear upon consideration of the following detail description and accompanying drawings, wherein:—

Figure 1 is a diagrammatic view of a part 20 of the mechanism included in the invention showing certain parts in plan and others in elevation.

Figure 2 is a detail view of the mechanism mounted upon the railway car to be operated by the operator of the car,

25 Figure 3 is a detail section through the switch element used in connection with the structure illustrated in Fig. 2,

Figure 4 is a plan view, substantially 30 diagrammatic showing the mechanism employed in operating the switches;

Figure 5 is a detail section taken approximately on the line 5—5 of Fig. 4,

Figure 6 is a section taken on the line 35 6—6 of Fig. 4,

Figure 7 is a detail view of the solenoids and gearing mechanism used in connection with the structure shown in Fig. 4,

Figure 8 is a detail view of one of the 40 switch elements,

Figure 9 is a cross section through the same,

Figure 10 is a longitudinal view of one 45 end of one of the switch elements showing its relation to the switch holding block, and

Figures 11 and 12 are plan views of the two different positions which the switch element assumes when changed from one position to another.

50 Referring to the drawings by numerals, the railway rails 1 and 2 are of the usual construction and the curved sections 3 and 4 are provided in the usual manner whereby the railway car may be diverted from the main line. Arranged at the points of inter-

section of the sections 3 and 4 with the main lines 1 and 2 respectively, are switch boxes 5, each of which contains a switch block 6 details of which are illustrated in Figs. 8, 9 and 10. Each block consists of 60 an elongated member substantially quarter cylindrical in cross section as shown in Fig. 9 thereby providing two flat surfaces 7 and 8. Trunnions or pintles 9 are provided on each end of the block whereby it 65 may be journaled in the ends of the block casing or housing 5 to permit it to be readily rotated. By referring to the drawing it will be noted that the surface 8 is provided with a longitudinal groove or channel 70 10, while the surface 7 is provided with a longitudinal groove or channel 11. The groove 10 is perfectly straight and is adapted to normally align with the main track 75 sections 1 and 2. The groove 11 is curved as shown so that the curve will conform to the curved track sections 3 and 4. Each block member 6 is provided with a tangentially extending arm 13 for the purpose of providing a connection with an operating 80 mechanism shown in detail in Fig. 4.

At convenient points between the rails, solenoids 14 are arranged mounted in any preferred manner as is well known in the electrical art, the housing or casing for the solenoids being arranged to conform to the conditions under which the invention is being used. The armatures 15 and 16 used in connection with the solenoids 14 each have a latch bar 17 and 18 connected thereto, the teeth of which are adapted to mesh with the teeth of a pinion 19 as shown in Fig. 7 of the drawing, so that as the solenoid is energized the rack bars 17 and 18 will be moved to impart a rotary movement to the gear 19. The gear 19 is mounted upon a vertical shaft 20 which extends through a supporting block 21, the latter being adapted to support a part of the mechanism and provided with longitudinal grooves 22 for the reception of the rack bars 17 and 18 so 90 that they may be guided in their longitudinal movement. The lower end of the vertical shaft 20 is provided with an arm 24 to which is connected an adjustable rack bar 25, the teeth 26 of which are adapted to engage the teeth of a ratchet gear 27 mounted on a convenient bearing 29 between the rails 1 and 2. In this connection 100 it should be understood that the mechanism 105 110

is located between the rails 1 and 2 and the general proportions may be varied to suit conditions.

The gear 27 has connected thereto an arm 30 which is adapted to swing with the gear and this arm in turn is connected by a suitable link 31 to a rack bar 32 which is laterally movable in engagement with a pinion 33 on the end of an operating shaft 34. The opposite end of the shaft 34 is provided with a crank 35 which is connected to operating rods 36 and 37 extending in opposite directions and connected to the arms 13 on the switch block 6.

15 Bearings 38 and 39 are employed to support the shaft 34, the bearing 39 being shown in Fig. 5 of the drawing. Attached to this bearing by a suitable pivot pin 40, is a double arm switch member 41 which has 20 its arms projecting in opposite directions below the shaft 34 and each end is provided with a switch plug 42, each adapted to contact with a switch contact member 43 connected to the electric wiring in the mechanism. In order that either one of these 25 switch elements may be held in contact, the shaft 34 is provided with an arm 44 having a ball 45 at one end to provide a weight for the end of the arm 44. This arm is movable 30 so that the ball will engage either one of the ends of the switch element 41 so that the shaft 34 may be turned to cause the ball 45 to weight either one of the ends of the arm whereby one of the switch elements will be 35 held closed while the other is held open.

Referring to Fig. 1 it will be noted that the solenoids 14, diagrammatically illustrated are connected by wires 43', 44', and 45' to contact plates 46, 47 and 48. Suitable 40 mechanism is carried by the railway car to make contact with the plates 46, 47 and 48 and this mechanism is illustrated in Fig. 2 of the drawing. A bracket member 49 supports a bell crank lever 50 which is connected at one end to a pressure rod 51, the latter being extended upwardly through the floor 52 of the car and provided with a plate 53 which may be engaged by the foot of the operator so that a downward pressure 50 may be applied to head of the bell crank lever 50. The bell crank lever 50 is also connected to a rod 55 which carries a contact shoe 56 at its terminal, the rod 55 being connected to the bell crank lever 50 through 55 the medium of a link 57. A bracket frame 58 carried by the car is provided with a cross pin 59 which normally maintains the rod 55 in an angular position as shown in Fig. 2 so that it can not be moved downwardly until a pressure is applied to the foot lever or plate 53. When such a pressure is applied, the contact shoe 56 will be thrust downwardly by virtue of the action of the bell crank lever and the shoe will 60 contact with anyone of the contact plates 46, 65

47 or 48 according to the position of the railway car. The upper end of the rod 66 is also connected to a lever 60 which is pivoted at 61 and carries a switch pin 62 which is adapted to engage and disengage a 70 switch element 63 included in the switch mechanism illustrated in detail in Fig. 3 of the drawings. The switch element 63 is provided with a lead 64 which extends to the car motor, said motor having its other 75 terminal grounded to the car, a resistance 65 being interposed between the switch and motor as shown in Fig. 2. A lead 66 extends from the switch element 62 to the contact shoe 56 to supply current to the contact plates 46, 47, or 48 when said shoe contacts therewith for energizing the solenoids to turn the switch blocks 6, said circuit being completed by the wires 67 and 68 connecting the opposite terminal of the connected solenoids to the contact members 43, one of which being closed by one of the contacts 42, which in turn is grounded by a wire running to one of the rails as indicated by the numeral 69.

It is to be noted that the circuit will remain completed until the switch blocks 6 have been completely thrown, the breaking of the circuit not occurring until the shaft 34 has completed its turning movement, 95 which is approximately one-half of one revolution, and the ball 45 engaging the other contact 42 on the arm 41. It can be seen that should the shoe 56 be disengaged from one of the contacts 46, 47, or 48 before the ball 45 has been swung over the dead center position, the ball 45 will fall back so that said switch blocks 6 will always be in one position or the other aligning with the rails when a car passes thereover.

105 Minor changes may be made in the details of construction without departing from the spirit of the invention or the scope of the claims hereunto appended.

110 What is claimed is:—

1. In combination with main track sections and curved track sections intersecting with the main track sections, rotary switch blocks disposed at the said intersection of the curved tracks with the main track, each rotary switch block comprising a substantially quarter cylindrical member having opposite flat surfaces, a straight groove formed in one surface whereby the sections of the main track may be longitudinally aligned, 115 a curved groove formed in the other surface of the block whereby one of the straight sections of the main line may be aligned through the groove with the curved section 120 of the track, each switch block being provided with a tangentially extending arm, operating rods connected to the arm, a crank shaft connected to the operating rod, and means to impart a movement to the crank shaft whereby both of the said blocks may 125 130

be simultaneously rotated when the shaft is actuated.

2. In combination with main track sections and curved track sections intersecting with the main track sections, rotary switch blocks disposed at the said intersection of the curved tracks with the main track, each rotary switch block comprising a substantially quarter cylindrical member having opposite flat surfaces, a straight groove formed in one surface whereby the sections of the main track may be longitudinally alined, a curved groove formed in the other surface of the block whereby one of the straight sections of the main line may be alined through the groove with the curved section of the track, each switch block being provided with a tangentially extending arm, operating rods connected to the arm, a crank shaft connected to the operating rod, and means to impart a movement to the crank shaft whereby both of the said blocks may be simultaneously rotated when the shaft is actuated, electrically operated solenoids, gearing mechanism associated with the solenoids to be actuated when the solenoids are energized and means connected to the gearing mechanism and to the said crank shaft whereby the latter may be rotated when the solenoids are energized, the said last mentioned means including a reciprocating rack bar, a pinion on the said crank shaft, the said rack bar being adapted to move in either direction and engage the said pinion whereby the crank shaft may be rotated in either direction to turn the said switch block to change the position of the said groove from an operative to an inoperative position.

3. In combination with main track sections and curved track sections intersecting with the main track sections, rotary switch blocks disposed at the said intersection of the curved tracks with the main track, each rotary switch block comprising a substantially quarter cylindrical member having opposite flat surfaces, a straight groove formed in one surface whereby the sections of the main track may be longitudinally alined, a curved groove formed in the other surface of the block whereby one of the straight sections of the main line may be alined through the groove with the curved section of the track, each switch block being provided with a tangentially extending arm, operating rods connected to the arm, a crank shaft connected to the operating rod, and means to impart a movement to the crank

shaft whereby both of the said blocks may be simultaneously rotated when the shaft is actuated, electrically operated solenoids, gearing mechanism associated with the solenoids to be actuated when the solenoids are energized and means connected to the gearing mechanism and to the said crank shaft whereby the latter may be rotated when the solenoids are energized, the said last mentioned means including a reciprocating rack bar, a pinion on the said crank shaft, the said rack bar being adapted to move in either direction and engage the said pinion whereby the crank shaft may be rotated in either direction to turn the said switch block to change the position of the said groove from an operative to an inoperative position.

4. A railway switch apparatus comprising in combination with a manually operated contact shoe carried by a railway car, contact plates disposed in the path of movement of said railway car, solenoids ordinarily deenergized and electrically connected to said contact plates whereby said solenoids will be energized when said contact shoe engages said contact plates, switch blocks operatively connected to said solenoids adapted to be moved for aligning certain track rails, a pair of contacts interposed in said electric circuit to said solenoids, a pivoted contact bar having a contact on each end thereof each adapted to engage one of said first mentioned contacts, means connecting said contact bar for completing the electric circuit to said solenoids, and a weighted member adapted to turn or complete the throwing said switch blocks should the current to said solenoids be broken due to said contact shoe carried by said railway car becoming disengaged from said contact plates before said switch blocks are completely thrown, said weighted member also adapted to engage the ends of said contact arm for making and breaking an electric circuit to said solenoids.

In testimony whereof, I have affixed my signature.

HARRY G. JOHNSTON.
